UNITED STATES PATENT OFFICE.

CHARLES A. MAY, OF TRENTON, NEW JERSEY, ASSIGNOR TO SPENCER M. ALPAUGH AND FRANK A. MAGOWAN, OF SAME PLACE.

DESIGN FOR A DECORATIVE PATTERN FOR DISHES.

SPECIFICATION forming part of Design No. 16,042, dated April 14, 1885.

Application filed November 22, 1884. Term of patent 3½ years.

To all whom it may concern:

Be it known that I, CHARLES A. MAY, a citizen of the United States, residing at Trenton, in the county of Mercer, in the State of New Jersey, have invented and produced a new and original Design for Dishes, of which the following is a specification, reference being had to the accompanying photograph, forming part thereof.

10 A represents the center, and B the border. The main portion of the border consists of a row of medallions, C, with ornamental edges, the medallions having a contrasting ground and displaying each a daisy with stem, spray, 15 and leaves, which show the color of the body of the ware on which they are placed. Between the medallions, and around them, are daisies with intertwined leaves and stems to a width greater than the length of a medallion, 20 and forming a continuous filling throughout the entire border. Outside of this portion of the border, and at or near the edge of the plate or other dish, is a waved or scalloped border, D, each scallop representing a perspective 25 view of half of a daisy, and showing a part of its center and the ends of the petals turned toward the eye.

The center ornament consists of a circular medallion, E, with contrasting ground, displaying in its center a spread daisy with sprays 30 and leaves surrounding it. Surrounding this medallion is a circle, from which spread out ornamental arms or extensions E', each terminating in a daisy, while springing from between these arms, and alternating with the 35 daisies, are sprays and leaves.

The leading features of my design are the combining of medallions, daisies, sprays, and the scalloped border-line in a border, and also the ornamental center-piece and its arrangement relatively with the border. 40

What I claim is—

1. The design for a dish, consisting of a decorative border and center, the border consisting of medallions having a contrasting ground and 45 displaying each a daisy, the medallions being equidistant from each other and surrounded by a continuous filling of daisies and intertwined leaves and stems, all placed within a waved or scalloped outside border-line, and 50 the ornamental center consisting of a medallion displaying a spread daisy and bearing ornamental arms or extensions, substantially as described and shown.

2. In a design for a dish, the decorative border consisting of medallions having a contrasting ground and displaying each a daisy, the medallions being equidistant from each other and surrounded by a continuous filling of daisies and intertwined leaves and stems, 55 60 and a circumscribing waved or scalloped border-line, substantially as shown and described.

3. In a design for a dish, the decorative center consisting of a medallion displaying a spread daisy and bearing ornamental arms or 65 extensions, substantially as described and shown.

CHAS. A. MAY.
